UNITED STATES PATENT OFFICE.

CHARLES E. HOPKINS, OF WILLIAMSPORT, PENNSYLVANIA, ASSIGNOR OF ONE-HALF TO JAMES W. SWEELY, OF SAME PLACE.

MACHINE FOR SAWING STEREOTYPE-PLATES.

SPECIFICATION forming part of Letters Patent No. 432,407, dated July 15, 1890.

Application filed January 24, 1889. Renewed June 13, 1890. Serial No. 355,272. (No model.)

To all whom it may concern:

Be it known that I, CHARLES E. HOPKINS, a citizen of the United States, residing at Williamsport, in the county of Lycoming and State of Pennsylvania, have invented certain new and useful Improvements in Stereotype-Plate-Sawing Machines, of which the following is a specification, reference being had therein to the accompanying drawings.

10 This invention relates to an improved device for separating stereotype-plates into suitable sections to be set up in the forms for printing. Heretofore said plates have been separated by sawing transversely across and 15 down through the plate from the type-face thereof between two parallel lines of type, the plate being held in a miter-box, by which the saw is guided. This method has been found objectionable for the reason that the 20 saw-teeth are apt to injure the edges of the face of the type, especially where the space between the lines of the type is narrow.

It is the object of my invention to obviate these objections; and to this end my invention 25 consists in a device by means of which the plate may be supported and accurately adjusted and partly sawed through from the back on a line with the space between two transverse parallel rows of type and afterward separated on such line, as more fully 30 hereinafter specified.

The above-mentioned object I attain by the means illustrated in the accompanying drawings, in which—

35 Figure 1 represents a perspective view of my improved device. Fig. 2 represents a transverse vertical sectional view thereof. Fig. 3 represents a detached perspective view of a vertically-movable gage-bar, forming part of 40 my improved device. Fig. 4 represents a plan view showing a modification of my device, and Fig. 5 represents a vertical sectional view of the device.

Referring to the drawings, the letter A indicates a vertical standard, which is preferably formed in two parts A' A², the bases of which are secured in any suitable manner to a horizontal support B. The said parts are provided with horizontal platforms C C', 45 which are flanged at opposite edges, as indicated by the letters c c', the said platforms

lying in the same horizontal plane and forming a horizontal support and longitudinal guide for the stereotype-plates, when the standards are secured to their table or support in 55 proper position. One of the standards in the face adjoining the opposite standard is provided with two vertical ways D, in which are arranged to slide, vertically, the guide-bars E, which are provided with rectangular recesses F near their lower ends, for the purpose 60 hereinafter explained. The adjoining faces of the two standards, near their lower ends, abut, as shown in Fig. 2 of the drawings; but above said abutting faces a space is left between 65 the standards in which the saw G may be reciprocated, the faces of the standards at the separated portions being recessed, as indicated by the letter d, to form guides for the back H of the saw, which consists of a rectangular bar, to which the blade is secured, as shown. The upper serrated edge of the saw is arranged to work between the upper adjacent faces of the standards, which 70 form a guide for the blade, so as to cause it to work accurately across the back of the plate to be separated. The flanges c of the platforms C and C' rise toward their adjacent faces, forming standards e e', between which is pivoted one end of a curved arm K, which 75 is provided with a dependent projection or arm L, to the lower end of which is pivoted a slotted lug m on a pressure-plate N, the lower face of which is adapted to bear upon the type-face of the stereotype-plate, to hold it to 80 the platform while the plate is being sawed from below. The said pressure-plate is provided with lugs or ears P at opposite ends, which rest upon the upper ends of the guide-bars E above mentioned, and so gage the saw 85 as to prevent the teeth thereof from cutting entirely through the stereotype-plate, as more fully hereinafter explained. The recesses in the guide-bars are so located with respect to the back of the saw that the upper ends of 90 said gage-bars always project beyond the serrated edge of the saw-blade, and by bearing against the under side of the pressure-plate prevent the saw from working through to the face of said stereotype-plate and injuring the 95 type thereon.

To the projecting ends of the back H of the

saw are pivoted the ends of a saw-carrying frame R, which passes through slots S in the lateral lugs T, projecting from the standards A A', before mentioned. Between the said

5 lugs and surrounding a portion of the longitudinal part of the saw-frame is located a spiral spring U, having bearings at its ends against the inner sides of the respective standards. The saw-frame at suitable points is 10 provided with pins V, which strike alternately against the opposite ends of the spring at the end of each stroke of the frame to give the frame a yielding impact at each stroke, the spring serving as a buffer to prevent injury to the parts of the device.

15 The letter W indicates an arm projecting from one end of the saw-frame, to which is secured a vertical handle, by means of which the saw may be manipulated.

20 In the modification shown in Fig. 4 the longitudinal portion of the saw-frame passes through suitable guide-openings in the lateral lugs, and the said frame is provided with buffer-springs X near each end for relieving 25 the shock of impact at each stroke of the frame.

The operation of my improved device is as follows: The stereotype-plate being placed face upward upon the supporting-platform 30 and adjusted so as to bring the proper portion over the saw, the pressure-plate is placed in position thereon and held down by one hand of the operator. The saw is then manipulated by the other hand with a gradually- 35 rising movement, cutting through the back of the plate until the ends of the guide-bars abut against the lugs on the pressure-plate, limiting the further upward movement of the saw. The plate thus partially cut through may then 40 be easily separated at the line of the saw-cut, either by breaking the parts asunder or cutting them with a suitable instrument, without any possible injury or defacement of the type.

45 Having thus described my invention, what I claim, and desire to secure by Letters Patent, is—

1. The combination, in a device for dividing and separating stereotype-plates into sections, of a reciprocating saw, a vertical guide for said reciprocating saw, a horizontal table or platform above the same whereon the plate may be adjusted, and a pressure-plate whereby the stereotype-plate may be held to the 50 action of the saw, so as to be cut transversely from the back thereof, substantially as specified.

2. The combination, with the reciprocating saw and vertical standard having vertical

ways for the passage of said reciprocating saw, of the guide-bars and vertical ways in which the same are arranged to slide, the horizontal table or platform for the reception of the plate, and the pressure-plate having lugs at each end adapted to bear upon the 65 upper ends of the vertical gage-bars, whereby the movement of the saw is limited so as to cut partially through the stereotype-plate from the back thereof, substantially as and for the purposes specified.

3. The combination, with the vertical standards and the flanged horizontal tables, of the guide-bars recessed near their lower ends, the saw-blade and its back, the saw-frame pivoted to the projecting ends thereof and provided with a handle whereby the saw may be manipulated, substantially as specified:

4. The combination, with the vertical standard, a reciprocating saw, and a saw-frame arranged to move in bearings in the vertical standard, of the buffer-spring surrounding the longitudinal portion of the saw-frame, substantially as specified.

5. The combination, with the guide-standard, of the saw reciprocating in ways therein, 85 the saw-frame pivoted to the back of said saw, the slotted lateral projections extending from the standard, and the intermediate coiled spring surrounding the longitudinal portion of the frame to receive the impact thereof, 90 substantially as specified.

6. In a machine for cutting stereotype-plates, the combination of a table, a reciprocating saw working below said table, the saw being capable of a vertical movement and 95 adapted to pass up through an opening in the table, and a pressure-plate arranged above the table, as and for the purpose described.

7. In a machine for sawing stereotype-plates, the combination of a flanged table, a reciprocating saw working below and capable of a vertical movement, a pressure-plate above the table, a pressure-arm K, pivoted upon the said table, this arm being pivotally connected to the said pressure-plate, substantially as described.

8. In a machine for separating stereotype-plates, the combination of a supporting-table, a longitudinally and vertically guided reciprocating saw, and guide-bars for limiting the movement of the said bar, substantially as described.

In testimony whereof I affix my signature in presence of two witnesses.

CHARLES E. HOPKINS.
